UNITED STATES PATENT OFFICE.

MAHLON B. GLADMAN, OF HOPKINS, MISSOURI.

SASH-BALANCE.

SPECIFICATION forming part of Letters Patent No. 295,630, dated March 25, 1884.

Application filed December 26, 1883. (No model.)

To all whom it may concern:

Be it known that I, MAHLON B. GLADMAN, a citizen of the United States, residing at Hopkins, in the county of Nodaway and State of Missouri, have invented certain new and useful Improvements in Sash-Locks; and I do hereby declare that the following is a full, clear, and exact description of the same, reference being had to the annexed drawings, 10 making a part of this specification, and to the letters and figures of reference marked thereon.

Figure 1 of the drawings is a perspective view of a window frame and sashes embodying my invention; Fig. 2, a detail view thereof, in perspective, with the frame and sashes in broken section; and Fig. 3, a detail view, in 15 perspective on an enlarged scale, of the plate and its attachments.

The present invention has relation to certain new and useful improvements in window-sash holders and fastenings; and the object thereof is to provide a simple and convenient means for raising or lowering the upper sash and holding it open at any point desired, or 25 securely locking it closed to the lower sash, whereby the operation of the device is rendered more convenient and reliable in its action. This object I attain by the construction substantially as shown in the drawings, 30 and hereinafter described and claimed.

In the accompanying drawings, A represents the window-frame, and B C the upper and lower sash, respectively.

To the sash B, at its top, is suitably connected one end of a cord, a, which passes over a grooved pulley, b, secured to the top of the window-frame, said pulley being supported in a swiveled hanger. The cord a extends down between a friction-roller, d, and a cam, 35 D, provided with a suitable handle for operating it, and are both pivoted to and between the upper cross-piece of the sash C and a plate, F.

Extending through the plate F and through the upper cross-piece of the sash E is a bolt, 45 G, a spring, e, being coiled around it, and its ends bearing against the face of the plate and an annular shoulder, f, on the bolt. The spring e causes the bolt G to be forced outward to engage with a hole, g, in the lower cross-piece, h, of the sash C when it is desired to 50 lock the two sashes together in a closed position, as found preferable.

Having now fully described my invention, what I claim as new, and desire to secure by Letters Patent, is—

In a sash holder and fastener, a cord secured

tion. A friction-plate, i, is secured to the cross-piece h, immediately over the hole g, and is perforated to register with the hole when secured in place. The cross-piece h of 55 the sash B is beveled in a direction toward the sash C, while the lower sash at its upper cross-piece, k, is beveled in an opposite direction, as shown in Fig. 2, so that when the two cross-pieces of the sashes come together a tight and 60 perfect joint will be formed. The beveling of the cross-piece h when the sash B is raised enables the cross-piece to ride over the end of the bolt G, the end of said bolt being beveled, as shown at l, to facilitate the joint operation 65 of the two, the spring automatically forcing the bolt in engagement with the hole g when brought in line therewith. The bolt G has a flange, m, extending some distance along its shank, which serves the twofold purpose of 70 a guide for the bolt and a stop to hold the bolt out of engagement with the upper sash, said flange working in a slot, n, extending radially from the opening in the plate F, through which the bolt passes; but when it is desired to hold 75 the bolt from engaging with the upper sash the bolt is pulled out a sufficient distance to enable it to be turned so that the outer extremity of the flange will rest on the plate. By pulling down on the cord a, after the sash 80 has been lowered its greatest extent, the sash B may be raised to any height and held at that point by the cam D, which is caused to firmly press the cord against the friction-roller d and wedge the cord between the roller and face of 85 the cam, the weight of the upper sash having a tendency to draw on the cord, which will cause it to be held by the cam with increased friction, and consequently still firmer. The lower sash can be also raised and held suspended at any desired height in the same manner, either independent of the upper sash or the two sashes raised together, so that the window will be open at both top and bottom, thereby providing a very simple and effective 90 means for operating the sashes, and holding them opened or securely locked in a closed position, as found preferable.

to the upper sash and passing over a pulley connected to the window-frame and extending down between a friction-roller and cam upon the lower sash, in combination with a spring-bolt to fasten the sashes closed, said bolt working in the same case with the cam, and having a flange extending a portion of its length, to serve both as a guide and stop, and extending through a plate with a slot projecting radially from the opening through which the bolt

passes, substantially as and for the purpose set forth.

In testimony that I claim the above I have hereunto subscribed my name in the presence of two witnesses.

MAHLON B. GLADMAN.
